[57] CLAIM

The ornamental design for a retractable cord reel dryer, as shown and described.

DESCRIPTION

FIG. 1 is a top perspective view of a retractable cord reel dryer showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The pattern of circular apertures is shown partially in FIG. 5 for ease of illustration and is understood to extend uniformly throughout the area represented.
